(57) **CLAIM**

The ornamental design for a fish shaped carabiner as shown and described.

DESCRIPTION

FIG. 1 is a top front isometric view of a fish shaped carabiner.

FIG. 2 is a bottom rear isometric view thereof.

FIG. 3 is a front side elevation view thereof.

FIG. 4 is a back side elevation view thereof.

FIG. 5 is a left side elevation view thereof.

FIG. 6 is a right side elevation view thereof.

FIG. 7 is a top view thereof; and,

FIG. 8 is a bottom view thereof.

The broken lines in the drawings show portions that form no part of the claimed design.

1 Claim, 5 Drawing Sheets
